UNITED STATES PATENT OFFICE.

CARL CULMAN, OF ST. LOUIS, MISSOURI.

COMPENSATION WATCH-BALANCE.

No. 798,993.

Specification of Letters Patent.

Patented Sept. 5, 1905.

Application filed November 25, 1904. Serial No. 234,262.

To all whom it may concern:

Be it known that I, CARL CULMAN, a citizen of the United States, residing at St. Louis, State of Missouri, have invented certain new 5 and useful Improvements in Temperature Adjustments for Balance-Wheels; and I do declare the following to be a full, clear, and exact description of the invention, such as will enable others skilled in the art to which it applies to make and use the same.

My invention relates to improvements in continuous or self-adjusting temperature compensations for the balance-wheels of chronometers, watches, and other timepieces; and 15 it consists in certain novel features of construction, combination, and arrangement of parts hereinafter fully described and claimed.

The object of my invention is to provide a simple and efficient device of this character 20 by means of which the air resistance offered by the balance-wheel will be automatically varied to compensate for the variation in the strength of the balance-spring and the size of the balance-wheel, which variation occurs as 25 the said parts expand and contract under changes of temperature.

The above and other objects, which will appear as the nature of my invention is more fully understood, are accomplished by the construction illustrated in the accompanying drawings, in which—

Figure 1 is a plan view of a watch-balance with my improvements applied thereto. Fig. 2 is a vertical sectional view taken on the line 35 2 2 in Fig. 1, and Fig. 3 is a similar view taken on the line 3 3 in Fig. 1.

Referring to the drawings by numeral, 1 denotes a watch-balance wheel of ordinary construction consisting of two segmental bi-40 metallic rim-sections 2, supported from the ends of an arm 3, which is attached to the balance-staff 4. The rim-sections 2 of the wheel are disposed in the usual manner, so that they form a perfect circle when in their normal positions, and have the usual weights or screws 45 5 connected to them, as shown. Extending through each of said rim-sections 2, adjacent to their ends and in substantially parallel relation with the main arm or bar 3, is a bar or 50 rod 6, which is preferably of steel. Each of said rods 6 passes freely through and slides in an opening 7, formed in the fixed end of one of the rim-sections, and has one of its ends screw-threaded, as at 8, to permit it to be ad-55 justably secured in a similarly screw-threaded

opening 9, formed in the free end of the said rim-section. Upon the opposite end of said rod outside of said rim-section is a head or weight 10, which may be of any suitable form.

It will be seen that when the parts are in 60 the position seen in Fig. 1 of the drawings and are adjusted for a moderate temperature the rim-sections 2 form a perfect circle, so that the air offers a certain resistance to the movement of the wheel, which resistance will of 65 course vary as the shape or size of the wheel varies when the rim-sections expand or contract under changes of temperature. When the temperature of the parts of the device lowers and the balance-spring contracts and 70 becomes stronger, the rim-sections will contract and change the shape of the wheel, and thereby lessen the amount of its resistance; but owing to the manner in which said heads or weights 10 are mounted this loss of resist-75 ance caused by the change in the shape of the wheel will be compensated for by the outward movement of said heads or weights. Similarly when the temperature rises and the balance-spring expands and becomes weaker the 80 rim-sections will expand to increase the air resistance; but this increase will be compensated for by the inward movement of the said heads or weights 10. It is thus seen that the wheel will be self-adjusting or automatic in 85 its compensation for the extremes or changes of temperature. By adjusting the length of the rods or bars 6, which carry the heads or weights 10, the wheel may be set or regulated 90 for any normal temperature, as will be readily understood.

From the foregoing description, taken in connection with the accompanying drawings, the construction and operation of the invention will be readily understood without re-95 quiring a more extended explanation.

Various changes in the form, proportion, and the minor details of construction may be resorted to without departing from the principle or sacrificing any of the advantages of 100 this invention.

Having thus described my invention, what I claim as new, and desire to secure by Letters Patent, is—

1. A balance-wheel having a rim-section secured at one end and having the opposite end free, and an approximately radially disposed compensating arm having one end secured to the free end of the rim-section, said compensating arm extending across the rim-section, 105 110

near the secured end of the latter, being free to move with relation thereto and having a weight at its free end.

2. A balance-wheel having a rim-section secured at one end and having the opposite end free, and an approximately radially disposed compensating arm having one end adjustably secured to the free end of the rim-section for longitudinal adjustment on said arm, the latter extending across the rim-section, near the secured end thereof, being free to move with relation to the secured end of the rim-section and having a weight at its free end.

3. A balance for chronometers, watches and other timepieces, comprising bimetallic, segmental arms or rim-sections, rods having their inner ends secured in the free ends of said arms and their outer ends extending transversely with respect to the fixed ends of said arms, and heads or weights upon the outer ends of

said rods, substantially as described and for the purpose set forth.

4. A balance - wheel for chronometers, watches and other timepieces, comprising a main arm, bimetallic, segmental rim-sections supported from the ends of said arm and formed with openings or slots adjacent to their fixed ends, adjustable rods screwed into the free ends of said rim-sections and passing freely through said openings or slots, and heads or weights upon the outer ends of said rods, substantially as described and for the purpose set forth.

In testimony whereof I have hereunto set my hand in presence of two subscribing witnesses.

CARL CULMAN.
